UNITED STATES PATENT OFFICE.

LOUISE M. PFUNDER, OF PORTLAND, OREGON.

DESIGN FOR A WORK-BAG.

48,947.

Specification for Design.

Patented Apr. 25, 1916.

Application filed December 17, 1915. Serial No. 67,480. Term of patent 7 years.

To all whom it may concern:

Be it known that I, LOUISE M. PFUNDER, a citizen of the United States, residing at Portland, in the county of Multnomah, State of Oregon, have invented a new, original, and ornamental Design for a Work-Bag, of which the following is a specification, reference being had to the accompanying drawings, forming part thereof.

I claim:

The ornamental design for a work bag, as shown.

LOUISE M. PFUNDER.

Witnesses:

W.M. C. SCHMITT,
CECIL LONG.
